UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,199,106.

Specification of Letters Patent. Patented Sept. 26, 1916.

Application filed May 24, 1916. Serial No. 99,487.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is, to provide a draft rigging of efficient operation.

In the drawings forming a part of this specification, Figure 1 is a side elevation of a draft rigging embodying my invention; Fig. 2 is a plan view, partly in horizontal section, on line 2—2 of Fig. 1, and showing the position of the parts in full buff; Fig. 3 is a cross section on line 3—3 of Fig. 1; Fig. 4 is a perspective view of the front follower; Fig. 5 is a perspective view of the draft gear shell.

Referring to the drawings, the numerals 6—6 indicate draft members, or parts of the car-frame to which the draft rigging is applied; 7 a horizontally disposed draft yoke mounted between the draft members. The draft yoke is a U-shaped member consisting of the limbs 8—8 and the rear connecting member 9. The limbs of the yoke are provided near their forward ends with the transverse slots 10—10 for the passage of the coupler key 11. The said coupler key extends through the draw bar 12, only the rear end thereof being shown in the drawings. The ends of the key 11 are received through slots 13—13 provided in the draft members. The slots 13 in the draft members are longitudinally extended to permit forward and rearward travel of the key therein, and the slots 10 in the limbs of the draft yoke are rearwardly extended to permit the rearward travel of the key 11 therein upon rearward movement of the draw bar without buffing strain upon the key. A draft gear 14 is mounted between the draft members, said draft gear having a shell 15, preferably a hollow cylinder in general form, and containing the friction elements 16, consisting preferably of the friction

shoes 17—17 and the wedge 18, and spring elements 19, consisting preferably of an outer coil spring 20 and an inner spring 21 nested therein, mounted within the shell. The springs are seated at their rear end against the preferably integral plate 22 closing the rear end of the shell, and at their forward ends against the friction shoes 17. A connecting bolt 23 has a head 24 at one end received in the rearwardly opening recess 25 provided in the rear plate 22 of the shell, and a nut 26 at its forward end received in the recess 27 in the forward face of the wedge 18. At its rear end the shell is preferably provided with flanges 28—28 extended from the rear plate 22 to permit the better engagement of the rear end of the shell with the connecting member 9 of the draft yoke 7. Intermediate its ends, the shell is provided with a preferably integral box-like member having the preferably flat lateral faces 29—29, and provided in its upper and lower faces with a transverse groove 30 formed between the vertically projected plates 31—31.

The front follower 32 comprises a transverse plate 33—33 having upper and lower rearwardly extending flanges 34—34, a pair of spaced-apart upper rearwardly extending arms 35—35, and a pair of lower spaced-apart rearwardly extending arms 36—36. The upper arms 35 are preferably integral with the upper plate 34, and the lower arms 36 are preferably integral with the lower plate 34. The rearwardly extended arms 35 and 36 are each provided with a lateral slot 37, the slots in the upper arms 35 being adapted to receive the upper key 38, the slots 37 in the lower arms 36 being adapted to receive the lower key 39. The key 38 passes through the upper groove 30 in the shell, and the lower key 39 passes through the lower groove 30 in the shell. The ends of the key 38 are received through slots 40, through adjacent portions of the draft members 6, and the ends of the lower key 39 are received through slots 41—41 in adjacent portions of the draft members 6. The slots 40 and 41 in the draft members are of suitable size to hold the respective keys 38 and 39 against longitudinal movement therein, thus making the keys 38 and 39 in the operation of the gear stationary in respect to the draft mem-

bers. The upper and lower grooves 30 with which the shell is provided are of suitable width between the plates 31—31 forming the said grooves to permit the forward movement of the shell in reference to the keys 38 and 39, the shell being adapted on forward movement of the draw bar to slide forwardly between the keys 38 and 39. The upper key 38 passes through the slots 37—37 in the upper arms 35 of the front follower, and the lower key 39 passes through the slots 37—37 in the lower arms 36 of the front follower. The slots 37 in the arms of the follower are longitudinally extended to permit the rearward movement of the arms upon the keys 38 and 39 on rearward movement of the draw bar. The limbs 8 of the draft yoke 7 extend forwardly of the front follower on either side of the vertical plate 33 of the front follower and pass between the upper and lower arms of the follower 35 and 36, respectively.

On rearward movement of the draw bar, the coupler key 11 slides rearwardly in the slots 10 in the draft yoke, the rear end of the draw bar engages against the front face of the plate 33 of the front follower forcing the front follower rearwardly. The front follower through its engagement with the friction elements is resisted in its rearward movement by said friction elements and the spring elements within the shell, the shell being stopped against rearward movement by the engagement of the front plate 31 thereof against the front edges of the keys 38 and 39, that is, the keys 38 and 39 engage against the front edges of the slots 30—30 of the shell, and the keys are held in a stationary position in relation to the draft members. On forward movement of the draw bar, the coupler key 11 engages against the forward ends of the slots 10 in the limbs of the draft yoke, the draft yoke is drawn forwardly and gives forward movement to the shell, which slides forwardly between the keys 38 and 39, the compression resisting elements in the shell being stopped by their engagement against the plate 33 of the front follower, the front follower being held against forward movement through engagement of the stationary keys 38 and 39 against the rear ends of the slots 37—37 in the upper and lower arms 35 and 36, respectively, of the front follower. It will be understood that on rearward movement of the front follower the arms thereof travel rearwardly in sliding engagement upon the keys 38 and 39.

I claim:

1. In a draft rigging for railway cars, the combination with draft members having upper and lower keys mounted between the same, of a front follower, the front follower being provided with upper and lower slotted arms slidably engaging the keys.

2. In a draft rigging for railway cars, in combination, draft members, upper and lower stationary keys between the draft members, a draft gear slidably mounted in reference to the keys, and a front follower 70 having upper and lower slotted arms slidably engaging the keys.

3. In a draft rigging for railway cars, in combination, draft members, upper and lower stationary keys between the draft 75 members, a draft gear slidably mounted between said keys, and a front follower having rearwardly extended arms in sliding engagement with said keys.

4. In a draft rigging for railway cars, in 80 combination, draft members, upper and lower stationary keys between the draft members, a draft gear slidably mounted between said keys, a front follower having upper and lower slotted arms, the upper arms 85 slidably engaging the upper key, and the lower arms slidably engaging the lower key.

5. In a draft rigging for railway cars, in combination, draft members, upper and lower stationary keys between the draft 90 members, a draft yoke, and a draw bar connected to the yoke, a draft gear and a follower, the draft gear having a shell having upper and lower transverse grooves, the stationary keys passing through said grooves, 95 the shell having a sliding movement between said keys, the draft yoke operatively connecting the shell to the draw bar.

6. In a draft rigging for railway cars, in combination, draft members, upper and 100 lower stationary keys between the draft members, and a draft gear shell, the draft gear shell having upper and lower outwardly opening slots to receive the keys.

7. In a draft rigging for railway cars, in 105 combination, draft members, upper and lower keys between the draft members, a draft gear shell slidably mounted between said keys, the shell having upper and lower outwardly opening transverse grooves for 110 the passage of the keys.

8. In a draft rigging for railway cars, in combination, draft members, upper and lower keys between the draft members, a draft gear slidably engaging said keys, a front follower having upper and lower arms vertically spaced apart and slidably engaging the keys, a draft yoke engaging the draft gear and having limbs passing between the upper and lower arms of the follower and the draw bar connected to the draft yoke. 115

9. In a draft rigging for railway cars, in combination, draft members, upper and lower keys secured between the draft members, a draft gear slidably mounted in reference to the keys, a draw bar, a draft yoke having limbs connected to the draw bar, a front follower having an upper pair and a lower pair of slotted arms slidably connected to the keys, the limbs of the draft yoke 120

130

passing either side of the front follower and between the upper and the lower arms thereof.

10. In a draft rigging for railway cars, in combination, draft members, upper and lower keys mounted between the draft members, a draft gear slidably mounted between said keys, a draft yoke, a draw bar connected to said yoke, and a front follower, the front follower being mounted within the draft yoke and having upper and lower arms slidably engaging the keys.

11. In a draft rigging for railway cars, in combination, draft members, upper and lower keys mounted between the draft members, a draft gear slidably mounted between said keys, a draft yoke, a draw bar connected to said yoke, and a front follower, the front follower being mounted within the draft yoke and having upper and lower arms slid-

ably engaging the keys, each limb of the draft yoke passing between an upper arm and a lower arm of the front follower.

12. In a draft rigging for railway cars, the combination with the draft members, of a pair of spaced, stationary keys between the draft members, a draft gear shell, and a follower, both the shell and the follower being slidable with respect to the keys and each other, the keys limiting the movement of the shell and follower in both directions.

13. In a draft rigging for railway cars, the combination with draft members, of a pair of horizontally extending stationary keys mounted between the draft members, a draft gear shell slidably mounted between the keys, and a front follower, the keys limiting the amount of movement of the shell and the follower.

JOHN F. O'CONNOR.
